United States Patent Office

Des. 215,870
Patented Nov. 4, 1969

215,870

COMBINED COOKING AND SERVING UNIT

Hans S. Singer, Spartanburg, S.C., assignor to HSS Corporation, Spartanburg, S.C., a corporation of South Carolina

Filed July 16, 1968, Ser. No. 12,785

Term of patent 14 years

Int. Cl. D7—02
U.S. Cl. D44—15

Fig. 2.

Fig. 1.

Fig. 3.

I claim:

The ornamental design for a combined cooking and serving unit, substantially as shown.
